COMBINED DIAL AND HANDS FOR A WATCH OR THE LIKE

Sondra J. Sicherman, Fresh Meadows, N.Y., assignor to Startime Watch Co., Inc., Roslyn, N.Y.

Filed Nov. 4, 1970, Ser. No. 25,810

Term of patent 14 years

Int. Cl. D10—07

U.S. Cl. D42—1

Fig. 2

FIG. 1 is a top plan view of a combined dial and hands for a watch or the like showing my new design; and FIG. 2 is an edge elevational view.

I claim:

The ornamental design for a combined dial and hands for a watch or the like, substantially as shown.
